UNITED STATES PATENT OFFICE.

HENRY J. IRWIN, OF JERSEY CITY, NEW JERSEY, ASSIGNOR, BY MESNE ASSIGNMENTS, TO THE CROWN CORK & SEAL COMPANY, INC., OF NEW YORK, N. Y., A CORPORATION OF NEW YORK.

CARBONATOR.

Application filed June 1, 1927. Serial No. 195,693.

The present invention relates to improvements in carbonators for charging beverages with carbonic acid gas, and includes a plurality of tanks into which the liquid and gas are fed under pressure and intimately mingled together by means of agitators, the invention being more particularly directed to means for removing the free air contained in the liquid which gradually accumulates in the apparatus and interferes with the proper action thereof.

Among the objects of the invention is to provide means for withdrawing the free air from the several tanks and collecting it in a separate chamber or trap from which it may be discharged in a substantially continuous manner.

For further comprehension of the invention, and of the objects and advantages thereof, reference will be had to the following description and accompanying drawing, and to the appended claims in which the various novel features of the invention are more particularly set forth.

25 Figure 1 of the drawing is a side elevation of the improved carbonator showing a general assembly of the several parts.

Figure 2 is a plan view thereof.

Figure 3 is a detail elevational view showing the air collecting chamber and air-releasing means.

In the drawing numeral 1 designates a base 1 arranged to support the lower carbonating tank 2 by means of the feet 3, a second tank 4 being mounted upon the lower tank by similar feet 5.

The tanks are provided at their opposite ends with stuffing-box bearings 6 in which are respectively mounted agitator shafts 7 and 8 provided in the usual manner with mixing blades fixed thereon and indicated by the dotted lines 9.

Also carried by the base 1 is a standard 10 provided with bearings arranged to rotatively support the shafts 11 and 12 upon which are respectively fixed the intermeshing driving gears 13 and 14. A motor 15 is carried on the top of standard 10 and is provided with a wide face pulley 16 adapted to transmit power through a shiftable belt 17 to the two pulleys 18 and 19, the latter being fast upon the shaft 11 while the pulley 18 is arranged to run loose thereon. The face of pulley 18 has a width corresponding with that of the belt 17, while

that of the fast pulley is of less width, whereby when the belt is shifted to the loose pulley the shaft 11 is inoperative, and when shifted to the fast pulley both the loose pulley and shaft are jointly rotatable.

For shifting the belt 17 a double arm lever 20 is pivotally mounted intermediate its ends on the bracket 21, fixed upon the standard 10, the upper end of the lever having a looped member 22 engaging the opposite side edges of the belt, while the lower end of the lever is pivotally connected to one end of a connection rod 23, the opposite end of the rod being hingedly connected to the lower end of an operating lever 24, pivotally mounted for swinging movement upon a pin 25 carried by an upright bracket 26, the latter being fixed to the base 1. At its upper end the operating lever 24 is provided with oppositely extending arms, one thereof carrying a regulating container 27 and the other a counterweight 28, the several parts being operated by the variation in height of the liquid within the lower tank 2.

For supplying the liquid to be carbonated, a pump 29 is fixedly secured to the standard 10 and provided with the usual inlet and outlet connections, the latter connection being indicated by the pipe 30 leading upwardly and delivering into the top of the upper tank 4, the supply or level of liquid therein being regulated by the overflow pipe 31, the upper open end of which is located below the upper wall of the tank to provide a space for the release of the air entrained in the circulation of the liquid. The lower end of the overflow pipe 31 leads into and provides the necessary means for supplying liquid to the lower tank 2, and from which latter tank the carbonated liquid may be drawn off in the usual manner as shown by the valve controlled pipe 32. In its passage through the tank 2 the liquid flows

90 through the flexible tube 33 and into the container 27 wherein it tends to find a level corresponding to that within the tank, and as such level varies in accordance with the rate 95 at which the carbonated liquid is drawn off, a corresponding variation of level will be had in the container 27, thus serving to vary the weight thereof, and effecting a raising and lowering action through the operating lever 100 24 to rock the latter and shift the belt 17 over the fast and loose pulleys 19 and 18 and thereby alternately operate and arrest the action of

pump 29. To provide for free circulation of the liquid between the container 27 and its connected tank, a flexible vent pipe 34 communicates between the top walls of the container and tank.

Carbonating gas is supplied to the tanks by means of a riser pipe 35 having branches 36 and 37 leading respectively to the upper and lower tanks, the several pipes being shown in part in dotted lines together with the regulating valves therefor. For mixing the gas and liquid together the agitator shafts 7 and 8, carrying the blades 9, are provided at one end with chain wheels 38 connected together with a driving chain 39, and for transmitting power to the upper agitator shaft 8 a chain-wheel 40 is detachably connected at one end thereof and driven by the chain 41 from the smaller wheel 42, fixed upon the hub of the continuously rotating loose pulley 18, the larger wheel 40 being provided with a clutch device 43 whereby its driven shaft 8 may be disconnected therefrom while the wheel continues to loosely rotate thereon, and thus provide means for arresting the agitator blades and the mechanical mixing of liquid and gas within the tanks. As shown in full lines in Fig. 1, the driving belt 17 engages the fast pulley 19 which drives through the gears 13 and 14 to rotate shaft 12, on the outer end of which is secured a crank-disc 44, having its crank pin connected through the rod 45 to the piston stem 46 of the pump 29 for the operation of the latter, the connection between the adjacent ends of the rod and stem being vertically slideable in the usual manner within the fixed guide member 47 secured to the standard 10. It will be clear that during the operation of the pump the loose pulley 18 will also be rotated by the overlapping position of the belt 17 on the said loose pulley. As the tank 2 becomes filled to a predetermined level by the action of the pump, the liquid will correspondingly rise in the container 27 and overbalance the counterweight 28 and cause the arm 24 to swing about its pivotal support 25 and operate through the connection rod 23 to swing the belt lever 20 and shift the belt 17 to a position on the loose pulley 18 clear of the fast pulley 19, and thus stop the action of the pump.

During the carbonating operation the liquid as fed under pressure from the pump to the several tanks tends during mixing action to release a certain amount of entrained free air that gradually rises and accumulates in the space at the top of the upper tank and interferes in a measure with the effective operation of the apparatus. For removing this air from the several tanks, a separate air chamber or trap 48 is provided having at its lower end a coupling connection 49 provided with an air pipe 50 extending upwardly therefrom to a point near the upper end of the

chamber adjacent the side wall thereof, the opposite ends of the pipe being open to admit the air at the top, and discharge it at the bottom into the valve-case 51, the latter being detachably secured at its upper end to the coupling connection by an ordinary screwed union 52 in a manner to effect a close joint against the pressure within the chamber 48. At its lower end the case is provided with a seat to receive the valve 53, the same being formed with a stem 54 projecting through the bottom wall of the case, and within the latter a compression spring 55 is mounted and arranged to effect at its opposite ends a pressure respectively against the lower face of the coupling connection 49 and valve 53 to yieldingly hold the latter in closed position against its seat. For the support of the several parts a bracket 56 is provided, the upper end thereof being secured to the valve-case 51 while its lower end is fixed to the bracket bearing 57 in which latter is rotatively supported the inner end of shaft 11. Loosely mounted on the latter shaft and in fixed relation with the chain wheel 42 is a cam 58, rotatable with the belt pulley 18, and engaging the cam is a lever 59 pivotally supported by the bracket 56, a contact screw 60 being adjustably threaded in the lever and disposed to engage the projecting valve-stem 54 and open the valve at each revolution of the cam in opposition to the spring 55, the latter closing the valve upon the release of the cam.

Leading into the upper end of air chamber 48 is an air or vapor pipe 61 having a connection 62 leading from the air or vapor space in the top of tank 4, the pipe being preferably coiled as indicated at 61a. During the open periods of the relief valve 53, the pressure within the tank forces the free air or vapor into the chamber 48, thence through the air pipe 50, valve-case 51 and discharges into the atmosphere through the free passage formed by the contracted portion of the valve case and loosely fitting valve stem 54, the amount of discharge at each opening movement of the valve being regulated by the contact screw 60 which may be adjusted by its screw thread to engage the valve stem and lift the valve to variable heights by the action of the cam 58. The air and vapor passing through the pipe 61 is directed downwardly into the chamber where the condensed vapor may settle to the bottom as indicated at 63 and be periodically drawn off by the cock 64, allowing essentially the free air to be discharged through the relief valve into the atmosphere. Communicating between the interior spaces at the top of the tanks 2 and 4 is a vent pipe 65 by means of which the free air and vapor arising in the lower tank may readily pass to the upper tank 4 and be discharged therefrom through the relief valve 53.

A drain pipe 66 and a safety valve 67 are

provided for the upper tank 4, and the usual mounting including pressure and liquid gauges are supplied to the tanks.

From the above described construction and operation of the carbonating device, the separation and discharge of the air and vapor collecting in the upper portion of the tanks may readily be accomplished, and the amount of such discharge adjusted to suit the character and conditions under which the carbonation of the liquid is effected, both with regards to periods during which the liquid supply is either maintained or interrupted, or with respect to the continuation or interruption of the agitating devices.

What I claim as my invention and desire to secure by Letters Patent, is:

1. In a machine for carbonating liquids including a carbonating tank, an air chamber disposed adjacent thereto and having an inlet connection at one end leading from said tank, a valve casing at the opposite end of said chamber, an air pipe within said chamber, one of the ends thereof opening into the valve case and the opposite end opening into said air chamber adjacent to and in disalignment with said inlet connection, and a relief valve in said casing.

2. An air and vapor chamber having an inlet connection at one end, a valve case at the opposite end thereof, an air pipe within said chamber, one of the ends thereof opening into the valve case and the opposite end opening into said chamber adjacent to and in disalignment with said inlet connection, and a relief valve in said casing.

3. In a carbonating tank, means for supplying liquid to said tank and forming therein a vapor and air space above the level of said liquid, an air chamber supported independently of said tank and having a pipe connection leading from said vapor and air space, means within said air chamber for separating the air and moisture in said vapor, and means for separately discharging said air and moisture.

4. In a carbonating machine, a plurality of mixing tanks supported one above the other, common means for supplying liquid to said tanks and forming therein vapor and air

spaces above the level of the liquid supplied thereto, the said vapor and air spaces communicating with one another, an air chamber supported independently of said tanks and having a pipe connection leading from the vapor and air space of the upper of said tanks, means within said air chamber for separating the air and moisture in said vapor, and means for separately discharging said air and moisture.

5. In a carbonating tank, means for supplying liquid to said tank and forming therein a vapor and air space above the level of the liquid supplied thereto, agitating means in said tank, an air chamber supported independently of said tank and having a pipe connection leading from the vapor and air space of said tank, means within said air chamber for separating the air and moisture in said vapor, and means for separately discharging said air and moisture.

6. In a carbonating tank, means for supplying liquid to said tank and forming therein a vapor and air space above the level of the liquid supplied thereto, a power shaft for actuating said liquid supplying means, an air chamber supported independently of said tank and having a pipe connection leading from the vapor and air space of said tank, means within said air chamber for separating the air and moisture in said vapor, and an air discharge valve connected to said air chamber and actuated by said power shaft.

7. In a machine for carbonating liquids including a carbonating tank, an air chamber disposed adjacent thereto and having an inlet connection at one end leading from said tank, a valve casing at the opposite end of said chamber, an air pipe within said chamber, one of the ends thereof opening into the valve case and the opposite end opening into said air chamber adjacent to and in disalignment with said inlet connection, a relief valve in said casing, and means for periodically actuating said relief valve.

Signed at New York in the county of New York and State of New York this 26th day of May, A. D. 1927.

HENRY J. IRWIN.
